CLAIM

The ornamental design for a shroud for plumbing fixture, as shown and described.

DESCRIPTION

FIG. 1 is a perspective view taken from the front, bottom and right side of a shroud for plumbing fixture embodying our new design;

FIG. 2 is a front elevational view thereof;

FIG. 3 is a right side elevational view, the left side being the mirror image of the right side;

FIG. 4 is a top plan view thereof;

FIG. 5 is a bottom plan view thereof; and,

FIG. 6 is a perspective view of the shroud for plumbing fixture in an unhooked and down position.

The fragmentary broken line representations of walls, hooks, sinks and cabinets in FIGS. 3 and 6 are for the purpose of illustration only and form no part of the claimed design.
